FIG. 1.

FIG. 4.

FIG. 2.

FIG. 3.

FIG. 5.

FIG. 6.

FIGURE 1 is a perspective view of a flood light for photographers or the like showing our new design, with mounting means and electrical cable shown in phantom;

FIGURE 2 is a front elevational view;

FIGURE 3 is a rear elevational view;

FIGURE 4 is a side elevational view;

FIGURE 5 is a top plan view;

FIGURE 6 is a perspective view showing another embodiment of our design wherein the flood lamp for photographers or the like is provided in a double form as shown.

The dominant features of our design reside in the portions shown in full lines, it being understood that the broken line representations of support poles are for purposes of illustration only.

We claim:

The ornamental design for a flood light for photographers or the like as shown and described.
